UNITED STATES PATENT OFFICE

WILLIAM D. FERRIS, OF STERLING, ILLINOIS, ASSIGNOR TO FRANTZ MANUFACTURING CO., OF STERLING, ILLINOIS, A CORPORATION OF ILLINOIS

DOOR OR WINDOW

Application filed November 25, 1929. Serial No. 409,476.

This invention relates to doors or windows, and more particularly to doors or windows that are hinged to swing about a vertical axis, and especially to so-called "French" doors or windows that are usually arranged to swing inwardly.

Generally stated, the object of the invention is to provide a novel and improved construction whereby a door or window of this general character, which opens inwardly, is mounted to move downwardly, in a closed position, so that its lower edge will extend a distance below the window or door sill, below a cleat on the window or door sill, thereby making the door or window weather-proof and water-tight, so to speak, at its lower edge, the door being movable upwardly a distance to permit it to swing inwardly over said cleat.

It is also an object to provide certain details and features of construction and combinations tending to increase the general efficiency and the desirability of swinging doors or windows of this particular character.

To the foregoing and other useful ends, the invention consists in matters hereinafter set forth and claimed and shown in the accompanying drawings, in which—

Fig. 1 is an inside view or elevation of a pair of "French" doors or windows involving the principles of the invention;

Fig. 2 is a horizontal section on line 2—2 in Fig. 1;

Fig. 3 is a vertical section on line 3—3 in Fig. 1;

Fig. 4 is a view similar to Fig. 3, showing the door or window in its raised position;

Fig. 5 is an enlarged front elevation of one of the hinges employed on said doors or windows, showing adjacent portions of the door or window and the frame;

Fig. 6 is a view similar to Fig. 5, showing the door or window in its raised position;

Fig. 7 is a horizontal section on line 7—7 in Fig. 5;

Fig. 8 is a vertical section on line 8—8 in Fig. 7;

Fig. 9 is a perspective of one portion of said hinge;

Fig. 10 is a perspective of another portion of said hinge; and

Fig. 11 is a perspective of another portion of said hinge.

As thus illustrated, the doors or windows 55 and 1 are hinged to swing inwardly, being attached to the door or window frame 2 by the upper hinges 3 and the lower hinges 4. There is clearance 5 at the upper edge of each door or window, whereby each door or window, when in closed position, may move a distance upwardly, in order that the lower edge 6 of the door or window may swing over the cleat 7, which is secured to the door or window sill 8 in the manner shown. The hinges 65 are constructed to permit this upward displacement of each door or window, as will hereinafter more fully appear; and when the doors or windows are in their closed positions, as shown in Fig. 3, the lower edge 6 is a distance below the top of the cleat 7, whereby the doors or windows are weather-proof or water-tight, so to speak, at their lower edges.

The upper hinges 3 each have an upper portion 9, which is secured to the door or window by screws 10, and a lower portion 11, which is secured to the door or window frame 2 by screws 12, whereby the lower part 11 is stationary, while the upper part 9 is movable with the door or window, the hinge pintle 13 being carried by the upper part and rotatable and slidably in the lower part.

Each lower hinge 4 comprises an upper section 14 which is secured to the door or window by screws 15, and a lower section 16 which is secured to the door or window frame 2 by screws 17, in the manner shown. The upper section carries the hinge pintle 18 and has a notch 19, as shown. The lower section 16 has a bearing portion 20 provided with a beveled top 21 provided with a notch 22 in the high side thereof, and the section 16 also has a notch 23, as shown. An intermediate section 24 has a bearing portion 25 formed with a beveled lower side 26, having a projection 27 to engage the notch 22 when the door or window is in raised position. This section 24 has a projection 28 which enters the notches 19 and 23 to lock the door or window.

dow in its lowered position. Also, the section 24 has a handle 29 for the operation thereof, and it will be seen that the pintle 18 extends through the bearing portions 25 and 20, thereby forming a hinge having a vertical axis.

When it is desired to open the door or window, the handle 29 is pulled outwardly and around in the position shown in Fig. 6 of the drawings, the two portions 20 and 25 having a cam action between them, which raises the door or window into the position shown in Fig. 4 of the drawings. In this position, the door or window can be swung inwardly over the cleat 7, as previously stated. When the projection 27 engages the notch 22, the parts are temporarily held in the position shown in Fig. 6 of the drawings, so that the door will not be liable to slip down when it is swung open.

Any suitable means can be employed for locking or latching the doors or windows in closed position. For example, an ordinary latching device 30 can be provided, as shown in Fig. 1 of the drawings.

When it is desired to shut the doors or windows, the two handles 29 are swung back into the positions shown in Figs. 1, 2 and 5 of the drawings, after the doors or windows have been swung into closed position, thereby permitting each door or window to move down a distance into the position shown in Fig. 3 of the drawings.

What I claim as my invention is:

1. In a hinge for mounting a closure to swing about a vertical axis, and to rise vertically to swing open about said axis, over a sill, hinge plates having interfitting knuckles provided with a vertical pintle and rotary means operative about said vertical axis to raise and lower the closure, said rotary means having a locking element to lock the closure in its lowered position.

2. In a hinge for mounting a closure to swing about a vertical axis, and to rise vertically to swing open about said axis, over a sill, hinge plates having interfitting knuckles provided with a vertical pintle and rotary means operative about said vertical axis to raise and lower the closure, said rotary means having means to retain the closure in raised position.

3. In a hinge for mounting a closure to swing about a vertical axis, and to rise vertically to swing open about said axis, over a sill, hinge plates having interfitting knuckles provided with a vertical pintle, and separate rotary means operative in one direction about said vertical axis to raise the closure, in the closed position thereof, preliminary to the opening thereof, whereby the closure when open is in raised position, and operative in reverse direction to lower the closure in closed position, said rotary means having a locking element to lock the closure in its lowered position.

4. In a hinge for mounting a closure to

swing about a vertical axis, and to rise vertically to swing open about said axis, over a sill, hinge plates having interfitting knuckles provided with a vertical pintle, and separate rotary means operative in one direction about said vertical axis to raise the closure, in the closed position thereof, preliminary to the opening thereof, whereby the closure when open is in raised position, and operative in reverse direction to lower the closure in closed position, said rotary means having means to retain the closure in raised position.

Specification signed this 20th day of November 1929.

WILLIAM D. FERRIS.
